UNITED STATES PATENT OFFICE.

ARTHUR B. LOW, OF DENVER, COLORADO.

PORTABLE VULCANIZING DEVICE.

1,187,436.

Specification of Letters Patent. Patented June 13, 1916.

Application filed January 12, 1916. Serial No. 71,780.

To all whom it may concern:

Be it known that I, ARTHUR B. Low, a citizen of the United States, residing in the city and county of Denver and State of Colorado, have invented certain new and useful Improvements in Portable Vulcanizing Devices; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to a portable vulcanizing device of the general character set forth in my previous Patent No. 1,163,629, dated December 7, 1915, and designated a portable vulcanizing package.

20 My object is in the present application to cover specifically a construction in which the pan or receptacle for the combustible or heat-producing element, shall be connected with the clamp in such a manner that it shall properly coöperate with the patch or the article to be mended or vulcanized, or both, during the vulcanizing operation. It is evident that in a construction of this class, the receptacle for the fuel or heat-generating or producing substance should be of such character that it may be employed for an indefinite number of vulcanizing operations. Hence, the pan or receptacle or holder for the combustible or heat-generating substance should be constructed with this idea in view.

In this application the invention will be described more particularly for use in applying a patch to the inner tube of a pneumatic tire though it is evident that the clamp and the fuel receptacle carried thereby may be employed in other relations. As illustrated and in the specific form to which this application will be more particularly directed, the pan or receptacle or holder for the combustible or heat-producing element, is connected in swiveled relation with the lower extremity of the screw of the clamp, so that as the screw is turned in the proper direction, the lower surface of the pan or receptacle containing the combustible or heat-generating element or substance, shall press upon the patch or upon any other article which it may be desired to subject to the necessary heat for vulcanizing purposes.

The patch may be applied to the lower surface of the pan or holder or may be separate therefrom as may be desired. If applied so that it will retain itself in position on the pan prior to the performance of the vulcanizing act, the manner in which it is connected with the pan should be such that the pan may release itself upon reversing the screw after the performance of the vulcanizing act.

Having briefly outlined my present improvement and in a general way indicated the function to be subserved thereby, I will proceed to describe the same in detail, reference being made to the accompanying drawing, in which is illustrated an embodiment thereof.

In this drawing,—Figure 1 is a side elevation of the invention. Fig. 2 is a section taken on the line 2—2, Fig. 1, looking downwardly or in the direction of the arrow. Fig. 3 is a side elevation partly in section illustrating the use of the vulcanizing device in applying a patch to the inner tube of a pneumatic tire, or other similar article. Fig. 4 is a fragmentary view partly in section illustrating the device used with a liquid combustible element, and shows a cover employed to extinguish the fire or flame at the close of the vulcanizing act while there is still a quantity of unused liquid. Fig. 5 is a side elevation partly in section showing a slightly modified form of construction. Fig. 6 is a view showing still another modification. Fig. 7 is a section taken on the line 7—7, Fig. 6, looking downwardly or in the direction of the arrow. Fig. 8 is a top plan view showing a pan equipped with a coil connected with a source of electricity for heating purposes.

The same reference characters indicate the same parts in all the views.

Let the numeral 5 designate a clamp having an approximately V-shaped body member composed of upper and lower arms 6 and 7 connected by a bend 8. The free extremity of the arm 7 merges into a relatively thin expanded part 9 which, as illustrated in Figs. 1 to 5 inclusive, of the drawing, is disk-shaped though it is evident that the particular shape or outline of this part is not material and that it may vary as desired or as the particular use for which it is intended, may dictate or require. To the upper surface of the disk 9 is applied a

layer 10 of some suitable non-heat-conducting substance, since it is desirable to conserve the heat as far as possible.

To the forward or free end of the arm 6 of the clamp is applied a screw 12 which is threaded into an opening formed in the adjacent end of the clamp. The upper end of this screw is fashioned as shown at 13 to facilitate manipulation while to its lower end is swiveled as shown at 14, a pan or receptacle 15 adapted to receive a combustible or heat-generating element. As shown in the drawing, this pan consists of a bow-shaped upper part 16 to whose extremities are secured by rivets or other suitable fastening devices 4, the body 17 of the pan or receptacle. It is preferred that the body of the pan be rigidly secured at the points 4 to the bow-shaped member 16 though if for any reason it may be desired, the pan may be pivotally connected with the bow-shaped arm. The swiveled connection 14 between the screw and the pan, should be of such character that the screw may turn freely when the pan is stationary.

In the form of construction shown in Fig. 4 a cover or lid 18 is illustrated, and is readily removable from the pan, its only function being to cover the top of the pan for the purpose of extinguishing the flame at the close of the vulcanizing act when liquid or other material 19 is employed, the quantity in the pan being greater than is necessary for a single vulcanizing act.

In the form of construction shown in Fig. 5, the pan which I will designate by the numeral 20, is of a slightly modified form of construction and is adapted more particularly for use with a liquid or semi-liquid combustible element. In this case the top of the pan is partly closed by a hood 21 having perforations 22 to supply the necessary air for purposes of combustion. This hood is brazed or otherwise suitably secured to the body 23 of the pan so that the two parts 21 and 23 are permanently connected to form a unitary structure. The screw 12 has a swiveled connection 24 with the hood of the pan, and co-operates with this form of pan in the same manner as in the previously described form of construction.

In the form of construction shown in Fig. 6, a number of clamp frames 25 is employed. To the forward extremities of the lower members of these frames is secured by riveting or in any other suitable manner, a plate 26 to which is applied a non-heat-conducting layer 27. The three screws 12 of the frame members 25, have their lower extremities respectively swiveled to bow-shaped members 28 which are all secured as shown at 29 to a relatively long pan 30. This construction is adapted for use in applying a relatively long patch, or in per-

forming the vulcanizing act on a relatively large surface area.

From the foregoing description the use of my improved vulcanizing device will be readily understood.

It is intended that gasoline, alcohol, lime, acid (to be used in combination with other suitable substances,) "solid" alcohol, or absorbent material such as paper saturated with salt peter, may be used in the pan or receptacle 15 or 30 as the case may be. In fact, any liquid, solid or semi-solid combustible, or heat-producing element, substance or article, may be employed in the pan or receptacle. In case saturated paper is used it may be inserted in the pan as needed. Such paper may, therefore, be sold separately from the vulcanizing device proper if it shall be commercially desirable. In case liquids are used, as gasoline or alcohol, they may be poured into the pan as needed. The pan may be fitted with a cover and solid alcohol, lime, or material which will react with acid or liquid alcohol or gasoline or oil or any combustible or heat-producing substance whatsoever may be placed in the pan, and in such quantity that it will not be necessary to charge the pan each time it is used, since one loading of the pan may if desired serve for several vulcanizing operations. It is evident that the size or shape of the pan may be such as may be found desirable or advantageous according to the circumstances of any particular case, or the specific use to be made of the device. As heretofore stated, it is not necessary that the vulcanizable material be fastened to the pan, as such may be placed on the rubber tube in position so as to cover punctures or openings made by ripping or tearing the tube, in which event the vulcanizing device is so arranged that the pan containing the heat-generating element may be screwed to position upon the vulcanizable material or patch.

It is evident that the pan which is fixedly connected with the clamp as heretofore explained, need not directly receive the combustible or heat-producing material, since cartridges containing such material may be inserted therein. Liquids may be inclosed in shallow pans with a cover on each pan, and these pans or holders for the heat-producing element may be placed within the pan or receptacle mounted on the clamp if desired. These auxiliary pans may be refilled or discarded as judged best.

Assuming that the vulcanizable element 31 (see Figs. 3 and 4) is in place, either directly upon the pan or upon the inner tube 125 or other article 32 to be mended or repaired, the pan containing the combustible element or heat-producing substance, is moved to position by adjusting the screw or screws, so that the pan shall be in contact with the vul-

canizable element. The combustible or heat-generating material is then lighted or otherwise treated for heat-generating purposes. This heat will act upon the vulcanizable ele-

5 ment, in such a manner as to properly perform the vulcanizing function whereby the element 31 or what is ordinarily termed the patch, may be made to adhere to the tube or other article 32 in such a manner as to vir-
10 tually form a part thereof, the vulcanizing function being efficiently performed. This operation requires but a few minutes, say from five to seven minutes. Furthermore, the operation may be performed by any per-
15 son no matter how unskilled he may be.

After the vulcanizing operation has been performed, if there is still a quantity of unused or heat-producing element in the pan, the flame must be smothered or otherwise 20 extinguished or the heat otherwise checked. This may be done by dropping a cover upon or over the top of the pan (see Fig. 4), or in any other manner that may be desired. The screw or screws of the clamp will then be 25 loosened and adjusted to raise the pan from the vulcanizable element, after which the vulcanizing device may be removed.

Attention is called to the fact that calcium carbid may be placed in the pan and when 30 it is desired to heat the pan or heatable member, a little water may be applied to the calcium carbid which will result in the generation of acetylene gas which may be lighted for heating purposes. Again, a resist-
35 ance coil 33 may be placed in the pan and connected with a suitable source of electricity.

In the drawing 39 designates a conventional source of electricity from whose op-
40 posite poles lead electrical conductors 37 and 38 to a plug 36 which is removably applied to terminals or electrodes 34 and 35 of the coil 33.

Attention is called to the fact that the pan 45 or heatable member has its bottom exte-
riorly concave in order to properly taper the outer edge of the patch and merge it into the adjacent surface of the tube 32 or other

device to which the patch or vulcanizable element is applied. 50

Having thus described my invention, what I claim is,—

1. A portable vulcanizing device comprising a clamp having two arms connected in operative relation and normally occupying 55 to each other the relation of upper and lower members, the lower member being expanded at its free extremity to form a support, while the upper member is equipped at its outer extremity with a holder open 60 to receive fuel in bulk for vulcanizing purposes, the said holder having a swiveled connection with the upper member and being movable toward and away from the expanded extremity of the lower member. 65

2. A vulcanizing device comprising a base having a seat for the article to be vulcanized, an arm supported from the base and projecting over the seat, a yoke pivotally supported from said arm, a vulcanizing bottom secured to said yoke and having a chamber to receive a heating medium, and means for causing said yoke and vulcanizing bottom to be pressed toward the base. 70

3. A vulcanizing device comprising a 75 yoke having a sheet metal vulcanizing bottom permanently attached thereto and chambered to seat a heating unit, a base, an arm supported from the base and from which said yoke is suspended, and means for causing said yoke to be pressed toward said base. 80

4. A vulcanizing device comprising a base, a ring shaped member having a bail, an open pan having a thin vulcanizing bottom to seat a heating unit, means rigidly 85 connecting said pan to said ring, and means from which said bail is suspended for moving said vulcanizing bottom toward and from the base.

In testimony whereof I affix my signature, 90 in presence of two witnesses.
